Primary Examiner — Rachel A. Voorhies*Assistant Examiner* — Benjamin D. Wannemacher(57) **CLAIM**

The ornamental design for a portable hole digger as shown and described.

DESCRIPTION

FIG. 1 is a front, right, and top perspective view of a portable hole digger, showing my new design;
 FIG. 2 is a rear, left, and bottom perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.

1 Claim, 8 Drawing Sheets(56)
